UNITED STATES PATENT OFFICE.

FREDERICK RAY, OF EAST ORANGE, NEW JERSEY, ASSIGNOR TO HENRY R. WORTHINGTON, OF NEW YORK, N. Y., A CORPORATION OF NEW JERSEY.

CENTRIFUGAL, TURBINE, OR SIMILAR PUMP.

No. 808,682.

Specification of Letters Patent.

Patented Jan. 2, 1906.

Application filed January 25, 1905. Serial No. 242,600.

To all whom it may concern:

Be it known that I, FREDERICK RAY, a citizen of the United States, residing at East Orange, county of Essex and State of New Jersey, have invented certain new and useful Improvements in Centrifugal, Turbine, and Similar Pumps, fully described and represented in the following specification and the accompanying drawings, forming a part of the same.

This invention relates to that class of centrifugal, turbine, or similar pumps in which inclosed impellers are used, the especial object of the invention being to avoid differences in pressure on opposite sides of the impeller, and thus prevent the end thrust which has heretofore existed in such pumps.

It is practically impossible to make the running conditions in the spaces on opposite sides of an inclosed impeller uniform; but differences in leakage from these spaces to the hub or in leakage from the delivery around the edges of the impeller exist, and these differences or other similar conditions result in a difference of pressure on opposite sides of the impeller, which frequently are large and are the chief cause of the end thrust which has heretofore existed and to balance which so many special devices have been designed. I avoid this chief cause of end thrust by providing an equalizing passage or passages between the spaces on opposite sides of the impeller, so that no substantial difference in pressure can exist in these spaces. This equalizing passage or passages between the spaces on opposite sides of the impeller may be provided in any suitable manner; but in a turbine-pump employing diffusing-vanes I preferably extend the passages through the diffusing-vanes, this being a simple and efficient construction.

The invention is applicable to pumps having either a single impeller or a series of impellers—that is, either single stage or multistage pumps; but the invention is especially important in connection with multistage pumps and will be illustrated and described in connection therewith.

In the accompanying drawings, forming a part of this specification, the invention is shown as applied in its preferred form to a multistage pump of a well-known type having two impellers, and this construction will

now be described and the features forming the invention will then be specifically pointed out in the claims.

In the drawings, Figure 1 is a section of the pump, taken longitudinally of the axis on the irregular line 1 1 of Fig. 2. Fig. 2 is a cross-section on the line 2 of Fig. 1.

Referring to said drawings, A is the pump-casing having the suction B and delivery C, and D' D² are the two impellers carried by the shaft E and separated by the usual diaphragms 10, forming, with the end casings, the impeller-chambers and the delivery-passage from the first to the second impeller. The impellers are shown as of a common inclosed type having the side walls 11 and vanes 12 extending between the side walls, and on opposite sides of the impellers are chambers 13, in which may or may not run vanes carried on the outside of the impeller-walls 11. These chambers 13 extend from the outer edge of the impeller inward to the packing-rings 1 in the running-joint which is formed between shoulders 2 of the impellers and shoulders on the end casings and partitions. The delivery of the first impeller D' passes outward from the impeller through the diffusion-ring F, having the diffusing-vanes 14, with passages 15 between them, through which the liquid passes from the impeller outward, as indicated by the arrows in Fig. 2, and then sidewise and downward through the passage 16 to the suction of the second impeller D², and the liquid from the second impeller passes outward through the similar diffusion-ring F, having vanes 14 and passages 15, to the delivery C. The impellers are preferably provided with the usual suction-balancing chambers 17, connected with the suction by passages 3, as shown.

The pump as thus far described is of a well-known type, and all the parts may be of any other common or suitable form.

The construction differs from that of present pumps of the type illustrated in that an equalizing connection is provided between the chambers 13 on opposite sides of the impeller, so that the liquid in these two chambers will be under substantially the same pressure notwithstanding any differences in running conditions on the opposite sides of the impeller. In the construction shown this connection is formed by passages through the diffusion-rings, as follows: Openings 4 are made at in-

5 tervals through the inner side flanges or plates 5 of the diffusion-rings F, which openings 4 are connected by holes 6, formed through the diffusing-vanes 14 at intervals, the openings 10 4, 6, with the spaces on opposite sides of the diffusion-rings, thus forming passages through which liquid may flow freely between the chambers on opposite sides of the impellers. Inequality of pressure on opposite sides of 15 the impellers outside the packing-rings 1 is thus prevented, and this cause of end thrust 20 fully avoided.

With impellers of the type shown, in which the suction is taken at one side of the hub, it 15 is desirable for full balancing of the impellers that some means should be provided for balancing the suction pressure at the hub. The construction shown with the suction-balancing chambers 17 and passages 3 is preferred for 20 this purpose; but other means may be used within the broader features of the present invention, and the invention, broadly considered, is applicable also with inclosed impellers of the double-suction type, in which the suctions 25 on opposite sides of the impeller balance each other. Only two impellers are shown; but the invention is applicable with any number of impellers.

It will be understood that the invention is 30 not limited to a pump having diffusion-rings, nor to making the equalizing connection through the rings, or providing it in any particular manner, but that this equalizing connection may be provided in any suitable manner to secure the desired result.

What I claim is—

1. A centrifugal, turbine or similar pump having an inclosed impeller and a pressure-equalizing connection between the opposite 40 sides of the impeller.

2. A multistage centrifugal, turbine or similar pump having a plurality of inclosed impellers and a pressure-equalizing connection between the opposite sides of each impeller.

45 3. A centrifugal, turbine or similar pump having an inclosed impeller and diffusing-vanes outside the impeller and a pressure-equalizing connection between the opposite sides of the impeller formed through the diffusing-vanes.

50 4. A multistage centrifugal, turbine or similar pump having a plurality of inclosed impellers and diffusing-vanes outside the impel-

lers, and a pressure-equalizing connection between opposite sides of each impeller formed 55 through the diffusing-vanes.

5. In a centrifugal, turbine or similar pump, the combination with an inclosed impeller taking suction on one side of the impeller, of a pressure-equalizing connection between the 60 opposite sides of the impeller, and suction-balancing means.

6. In a centrifugal, turbine or similar pump, the combination with an inclosed impeller taking suction on one side of the impeller, of a 65 pressure-equalizing connection between the opposite sides of the impeller, and a suction-balancing chamber on the back of the impeller communicating with the impeller-suction.

7. In a multistage centrifugal, turbine or 70 similar pump, the combination with a plurality of inclosed impellers, of a pressure-equalizing connection between the opposite sides of each impeller, and suction-balancing means.

8. In a multistage centrifugal, turbine or 75 similar pump, the combination with a plurality of inclosed impellers, of a pressure-equalizing connection between the opposite sides of each impeller, and a suction-balancing chamber on the back of each impeller communicating with the impeller-suction.

9. A centrifugal, turbine or similar pump having an inclosed liquid-impeller and a pressure-equalizing connection permitting the passage of liquid 85 between the opposite sides of the impeller.

10. A multistage centrifugal, turbine or similar pump having a plurality of inclosed liquid-impellers, and a pressure-equalizing connection permitting the passage of liquid 90 between the opposite sides of each impeller.

11. A centrifugal, turbine or similar pump having an inclosed liquid-impeller taking suction on one side of the impeller, a pressure-equalizing connection permitting the passage 95 of liquid between the opposite sides of the impeller, and a suction-balancing chamber on the back of the impeller communicating with the impeller-suction.

In testimony whereof I have hereunto set 100 my hand in the presence of two subscribing witnesses.

FREDERICK RAY.
